UNITED STATES PATENT OFFICE.

CHARLES KNOX HARDING, OF CHICAGO, ILLINOIS.

PROCESS FOR POPPING CORN.

1,104,990.

Specification of Letters Patent. Patented July 28, 1914.

Application filed November 23, 1912. Serial No. 733,213.

To all whom it may concern:

Be it known that I, CHARLES KNOX HARDING, a citizen of the United States, residing at Chicago, in the county of Cook and State 5 of Illinois, have invented certain new and useful Improvements in Processes for Popping Corn, of which the following is a specification.

My invention relates generally to improvements in the art of treating starchy cereals for food, especially pop-corn for which it is particularly fitted.

The object of my invention is to cook, disrupt, enlarge and expand the starchy interior of the pop-corn to as great an extent as possible, and to facilitate, regulate, control and insure uniformity in maintaining improved conditions in popping corn.

My invention further comprises new and useful features of the process, as will be hereinafter shown, described and pointed out in the claim.

The embodiment of my invention illustrated in the accompanying drawings shows 25 an apparatus adapted for continuous working—that is, feeding the unpopped corn in a continuous stream, passing it steadily to a point in the popping chamber, while it is subject to the action of both the heat and 30 a rapidly flowing current of a gaseous medium, such as air, preferably rarefied much below the atmospheric pressure, at the point where the grains explode into many times their original volume; the current of rarefied air immediately carries them out of the 35 popping chamber and the zone of highest temperature, which may be heated more intensely than in the old intermittent process, where the popped and unpopped corn both 40 were exposed for a time together.

I have found that the best results are produced by heating up the grains of corn as rapidly as possible to a high temperature, thereby preventing the high pressure vapors 45 from leaking or diffusing through the exterior hull of the kernel. The maximum interior vapor pressure attainable is limited by attaining that temperature at which the 50 hull is scorched or carbonized, and this partial destructive distillation breaks down the mechanical strength of the hull and the kernel explodes, or pops, at this temperature.

As it is desirable to disrupt, distend and expand the starchy interior as much as possible, and it is difficult to increase the in-

ternal vapor pressure beyond a certain temperature, according to my invention I reduce the external gaseous pressure to which the kernel is exposed at the moment of popping to a point where the volume assumed by the 60 liberated vapor becomes many times as large as it would be if suddenly liberated against the atmospheric pressure. It is well known that steam at 1.47 lbs. absolute pressure occupies ten times the volume it would at ordinary atmospheric pressure, 14.7 pounds. 65

The drawings show a central vertical section of an apparatus in which my process may be employed.

The cylindrical popping chamber 1 is 70 preferably formed of hard glass, or fused transparent silica so that the operation may be readily observed. The unpopped corn is fed from the hopper through the feeding valve 9 into the end of the cylinder 1, and is 75 gradually advanced toward the opposite end by the stirrer 8. The blower 3 discharges a rapidly flowing current of air through the popping chamber, which carries away the popped corn and deposits it in the receiving 80 chamber 2, which may be constructed of glass.

Fig. 4 shows a heating chamber for applying heat to the circulating air, one end of which communicates with the inlet opening 85 of the blower 3, and the other end is continued to the top of the receiving chamber 2, which forms a part of a continuous passage through which the current of air circulates. The heater tube 4 is heated by the 90 gas burner shown at 5. The lower portion of the popping chamber 1 is provided with the electric heater 6 which is shown as being formed from coils of high resistance wires backed by a lining of refractory and insulating material adapted to radiate heat into the popping chamber and rapidly impart a 95 high temperature to the kernels.

In operation, the unpopped corn is fed through the feeding valve 9 and is subjected 100 to the action of the radiant heat from heater 6, at the same time the fan produces a rapid flow of air which is drawn through the heater tube 4 and heated to a relatively high 105 temperature. The velocity of the flowing air is sufficient to carry the popped corn out of the popping chamber and into the receiver, where its velocity is materially reduced and the popped corn falls to the lower portion of the receiver tube, the heated air continues 110

upwardly and finally passes downward and back through the heater tube 4, and is thus continuously passing through the blower and thus maintained in circulation and enough heat applied to it to maintain its temperature so that it will not have a cooling effect. Fig. 11 shows an outlet which communicates through a cooling coil with an air pump for removing a large part of the air and pressure from the interior of the apparatus and to remove the excess air which enters by leakage and the operation of the feeding valve 9 and also the operation of the discharging valve 7, which operates in a well known manner for removing the popped corn from the lower part of the receiving chamber 2 while allowing the minimum amount of air to enter. Any of the corn which fails to pop is passed on through the

popping chamber by the stirrer and falls 20 into the trough 10.

Having now described my invention, what I claim is:—

The process of popping corn, which consists in producing pressure within the kernels by the application of heat and exploding the kernels while maintaining a gaseous pressure on the exterior of the kernels less than normal atmospheric pressure.

In testimony whereof, I have signed my name to this specification in the presence of two subscribing witnesses, this 21st day of November, A. D. 1912.

CHARLES KNOX HARDING.
